ATTORNEY

UNITED STATES PATENT OFFICE.

JOHN J. LAWLESS, OF ATLANTIC CITY, NEW JERSEY.

SOLDERING TORCH.

Application filed April 28, 1927. Serial No. 187,312.

This invention relates to blow torches particularly those of the readily portable type, and has for its object the provision of a novel blow torch designed particularly for 5 use by electricians and others, the device being so constructed and arranged that it may be readily carried about in a tool box or in the user's pocket and capable of being set down or laid down upon a support without likelihood of its falling off and becoming subsequently damaged as a result there- 10 of.

An important object is the provision of a blow torch which is adapted to use alcohol, 15 gasoline or the like as a fuel, the device embodying a wick dipping down into the fuel reservoir so that a constant feed of fuel will be supplied to the flame, and another feature being the provision of a blow pipe 20 discharging adjacent the flame and adapted to have air forced therethrough by the lungs of the user whenever it is necessary to provide a very hot flame for soldering or other similar purposes.

25 Another object of the invention is to provide a device of this character which is provided with flint and steel means whereby ignition may be readily effected, it being consequently unnecessary that the operator 30 be provided with matches in order to start the device.

An additional object is to provide a device of this character which will be simple and inexpensive in manufacture, easy to use, 35 positive in action, efficient and durable in service, and a general improvement in the art.

With the above and other objects and advantages in view, the invention consists in 40 the details of construction and the arrangement and combination of parts to be hereinafter more fully described and claimed, and illustrated in the accompanying drawings, in which:

45 Figure 1 is a vertical longitudinal section taken through the device.

Figure 2 is an edge elevation, and

Figure 3 is a bottom plan view.

Referring more particularly to the drawings, I have shown the device as comprising 50 a main casing 10, which is constructed preferably of suitable sheet metal enameled, nickel-plated or otherwise treated to have a pleasing appearance and to be free from 55 likelihood of corrosion or rusting. This casing 10 is preferably rectangular in shape,

so that in case it is laid down upon the top of a step-ladder or bench or other support, it cannot roll off as would be the case if it were of cylindrical or other curved cross sectional shape. Clearly, this casing 10 may be constructed in one piece or in any desired number of pieces to be secured together as by soldering, welding or the like, there being absolutely no limitations in this respect 60 inasmuch as these pieces are purely mechanical details. At its top wall 11, this casing 10 is provided with an opening surrounded by an upstanding flange 12 and within this opening is mounted the burner structure to 65 be described.

The casing 10 constitutes a reservoir within which is contained a suitable supply of fuel, such as alcohol, gasoline or the like, the former being probably preferable as being less likely to explode. The interior of the flange 12 is threaded and screwed thereto is a thimble 13 of cylindrical form provided intermediate its ends with an angular portion 14 for the purpose of facilitating an 70 engagement of a wrench thereon for turning purposes. This thimble extends partly into the casing and partly above the same and is of course provided with an opening therethrough within which is mounted a 75 sleeve 15 which constitutes a carrier or guide for a wick 16 of any ordinary or preferred type, the intention being that the upper end of the wick extend above or beyond the sleeve 15 so as to permit combustion at this 80 point. The length of the wick may of course be varied and will vary as it is used or burned away but initially it is intended to be of specific length to extend down into the casing 10 and possibly even lie upon the bottom thereof, this detail being immaterial. It is preferable that the guide sleeve 15 be provided at its bottom with openings 17 and near its upper portion with other openings 18, the latter being provided for the pur- 85

pose of preventing the fuel in liquid stage from rising to the top of the wick, the intention being that the fuel really be gasified at the upper end of the wick rather than remaining in its liquid state. To cover the wick when the device is not in use, I preferably provide a cap or hood member 19 adapted to be disposed in enclosing relation to the wick and to the guide sleeve 15 and detachably screwed upon the upper end 100 of the thimble 13. It is also advisable to provide a chain or other similar flexible 105

member 20 connected at one end with the hood or cap having its other end connected with the casing 10 for the purpose of preventing the cap or hood from becoming lost.

5 An important feature is the provision of a blow pipe which includes or comprises a tube 21, preferably of metal mounted upon the side of the casing 10 as by clips 22 and bent or shaped to have its upper end portion disposed adjacent the wick guide or sleeve 15. This upper end of the tube 21 is closed as shown at 23 but is provided at one side with a hole 24 located opposite the end of the wick so that when air pressure 15 is supplied to this tube, the air will pass out therefrom and transversely across the flame at the end of the wick. A suitable rubber tube or hose 25 is connected with the tube 21 and may be placed in the mouth of 20 the operator whenever it is necessary that he have a forced draft to obtain a blast effect. Clearly, if compressed air is available the rubber tube 25 may be connected with the source of compressed air instead of being 25 blown into by the operator.

Another important feature of the invention is the provision of igniting means which will make the use of matches unnecessary. In carrying out this detail, I provide a block 30 or piece of flint 26 mounted within a frame structure or bracket 27 located on one side of the casing 10, this bracket or frame structure being formed with an opening 28 exposing a considerable area of the flint. This 35 igniting feature also comprises a tubular supporting member 29 adapted to be screwed into a threaded opening formed in a flange 30 in the top of the casing when it is not in use, the member 29 having a knob or other similar handle 31 at its upper end and having its lower end carrying a piece of hard steel 32. The member 29 is of tubular form and is adapted to be filled with absorbent material capable of being saturated with alcohol, gasoline or the like, the material exposed adjacent the hard steel point 32. Clearly, when the device 29 is removed from the casing and the hard steel point 32 rubbed or struck upon the flint 26, a spark will be 45 produced which will ignite the absorbent packing and produce a sufficient flame to effect ignition of the main wick 16. When the wick 16 is burning, or when a flame ex-

ists at the upper end thereof, it is clear that this flame may be used for soldering purposes and in case of necessity the operator may blow through the tube 25 in order to get a blast effect which will readily effect melting of any solder necessary to use.

Another feature of advantage is that the device provides or embodies a support so that it cannot be readily tipped over. This may consist simply of an elongated spring member 33 pivoted at 34 upon the bottom of the casing 10 and normally lying within a recess 35 formed by striking the bottom upwardly or inwardly, this spring 33 being capable of being sprung and moved transversely into the position shown by dotted lines in Figure 3 so as to make the device 60 more stable when set upon a table, top of a step-ladder or other support.

From the foregoing description and a study of the drawings, it will be apparent that I have thus provided a very simply 65 constructed, inexpensive and easily operated and controlled device for the purpose specified, which will possess all the features of advantage set forth. It is really believed that the construction, operation and advantages will be readily apparent to one skilled 70 in the art without further explanation.

While I have shown and described the preferred embodiment of the invention, it should be understood that I reserve the right 75 to make such changes in the form, construction and arrangement of parts as will not depart from the spirit of the invention or the scope of the subjoined claim.

Having thus described the invention, I 80 claim:

In a torch of the character described, a casing serving as a fuel reservoir, a thimble detachably mounted within the top of the casing, a guide slidably mounted within the 85 thimble, a wick within the guide, and a blow-tube mounted exteriorly upon the casing in longitudinal relation thereto and having one end closed and terminating adjacent the wick, said tube being formed in its side 100 toward the wick with an air discharge opening whereby a current of air may be forced transversely of the flame at the wick.

In testimony whereof I affix my signature.

JOHN J. LAWLESS.
